UNITED STATES PATENT OFFICE.

DUANE ARMSTRONG, OF ROCHESTER, NEW YORK.

DESIGN FOR A LEGGING.

SPECIFICATION forming part of Design No. 27,005, dated April 27, 1897.

Application filed October 20, 1896. Serial No. 609,468. Term of patent 7 years.

To all whom it may concern:

Be it known that I, DUANE ARMSTRONG, a citizen of the United States, residing at Rochester, in the county of Monroe and State of New York, have invented and produced a new and original Design for Leggings, of which the following is a specification, reference being had to the accompanying drawing, showing a perspective view thereof.

The leading feature of my design consists of a legging shaped to conform to the human leg between the knee and ankle—that is, tapering from the top toward the bottom and having lapped edges at the side and a vertically-extending opening at the rear.

The general shape of the legging when extended, as shown, is that of the human leg between the knee and ankle, tapering from the top toward the bottom, and composed of

the parts A and B, the edges of which are lapped at the side of the legging and connected by fastening devices, (indicated by buttons C,) visible when the parts are lapped, as in full lines. A vertically-extending opening is formed at the rear of the legging between the edges of the parts A and B, and these proximate edges are provided with openings or eyelets for a lacing D, (indicated in dotted lines;) but the particular direction taken by the lacing is not an essential characteristic of the design.

I claim—

The design for leggings substantially as herein shown and described.

DUANE ARMSTRONG.
